UNITED STATES PATENT OFFICE.

JOSEPH W. CALEF, OF NORTH EASTON, MASS., ASSIGNOR OF ONE-HALF OF HIS RIGHT TO AUSTIN DEMMONS CABLE, OF MONTREAL, CANADA.

WRENCH.

SPECIFICATION forming part of Letters Patent No. 226,490, dated April 18, 1880.

Application filed January 31, 1880.

To all whom it may concern:

Be it known that I, JOSEPH WARREN CALEF, of North Easton, in the county of Bristol and State of Massachusetts, have invented certain new and useful Improvements in Wrenches; and I do hereby declare that the following is a full, clear, and exact description of the invention, which will enable others skilled in the art to which it appertains to make and use the same, reference being had to the accompanying drawings, which form a part of this specification, and in which—

Figure 1 is a side view of a wrench embodying my improvement. Fig. 2 is an edge view of the same. Fig. 3 is a section through Fig. 2. Fig. 4 is a section through Fig. 1. Fig. 5 is a perspective view of the sliding jaw detached.

Similar letters of reference indicate corresponding parts in all the figures.

This invention has relation to self-adjusting wrenches; and it consists in the construction and combination of parts, as hereinafter fully described, and particularly pointed out in the claim.

In the drawings, A is the stem or shank, which is inserted into a wooden handle, B, and secured by a nut, b, at its lower end. The projecting upper part of the shank, above its cylindrical head A², is flattened, as shown at A², and provided with two diverging lugs or ears, a a, and a perforation, c. The outer jaw consists of two plates or parts, C C, united on one side by the solid jaw-piece D, which is provided with a laterally-projecting flange, d. The opposite inside faces of the jaw-plates C C have parallel grooves e e and perforations f f, which register with the aperture c in the upper part of the shank, and the jaw, consisting of the parts C C D, is pivoted upon the flattened head A² by means of a pin, E. The adjustable sliding jaw consists of a sliding bolt, F, which is provided with two parallel flanges, g g, one on each side, which fit into the grooves e e of the jaw plates or blades C C. The under side of bolt F has two notches or recesses, h h, which receive the ears a a of the flattened head A², as shown in Fig. 3, and its upper side is provided on one end with the jaw-piece G, which is made with a flange, d,

in like manner as jaw D, the flanges d d being opposite to and registering with each other.

The jaws or lugs d d are set back from the face of the jaws D G, so that there may be left a projecting portion of said jaws D G, to operate as a stop for the nut or whatever is grasped by jaws or lugs d d.

I prefer to make the faces of the jaws D G partly serrated, to enable them to get a better bite on the nut operated upon, and partly smooth, so as to avoid the abrasion of painted or otherwise finished surfaces, if the wrench is used on such.

From the foregoing description, taken in connection with the drawings, the operation of my invention will readily be understood without further explanation. By simply turning the handle the jaws will adjust themselves upon the nut or pipe, as the case may be.

Instead of two lugs or ears, a a, as shown in the drawings, a larger number may be used, the bolt F being made with a corresponding number of recesses; but for ordinary purposes two will be found to be sufficient. If more than two are used, they should be disposed in a segment or half-circle around pin E as a center, so as to operate with ease.

The projecting flanges d d enable the wrench to be used on carriage and other work where the jaws D G could not well be applied.

Having thus described my invention, I claim and desire to secure by Letters Patent of the United States—

The wrench composed of the handle A, with its outer end provided with teeth a a of jaw D, having on each side of the teeth side pieces, C, having opposite parallel grooves e, and having a lateral flange, d, and sliding rack-jaw F G, having flanges g and a lateral flange, d, the flanges d d being set back from the face of the jaws D G, as and for the purpose set forth.

In testimony that I claim the foregoing as my own I have hereto affixed my signature in presence of two witnesses.

JOSEPH WARREN CALEF.
